(57) **CLAIM**

What is claimed is the ornamental design for a combined tablet device base and lid, as shown and described herein.

DESCRIPTION

FIG. 1 is a front perspective view of a combined tablet device base and lid shown in an open position;

FIG. 2 is a top view of the combined tablet device base and lid shown in FIG. 1;

FIG. 3 is a bottom view of the combined tablet device base and lid shown in FIG. 1;

FIG. 4 is a left-side view of the combined tablet device base and lid shown in FIG. 1;

FIG. 5 is a right-side view of the combined tablet device base and lid shown in FIG. 1;

FIG. 6 is a front-side view of the combined tablet device base and lid shown in FIG. 1;

FIG. 7 is a rear-side view of the combined tablet device base and lid shown in FIG. 1;

FIG. 8 is a front perspective view of a combined tablet device base and lid in an alternate, closed position with the tablet device lid face up;

FIG. 9 is a top view of the combined tablet device base and lid shown in FIG. 8;

FIG. 10 is a bottom view of the combined tablet device base and lid shown in FIG. 8;

FIG. 11 is a left-side view of the combined tablet device base and lid shown in FIG. 8;

FIG. 12 is a right-side view of the combined tablet device base and lid shown in FIG. 8;

FIG. 13 is a front-side view of the combined tablet device base and lid shown in FIG. 8;

FIG. 14 is a rear-side view of the combined tablet device base and lid shown in FIG. 8;

FIG. 15 is a front perspective view of a combined tablet device base and lid in an alternate, closed position with the tablet device lid face down;

(Continued)

FIG. 16 is a top view of the combined tablet device base and lid shown in FIG. 15;
 FIG. 17 is a bottom view of the combined tablet device base and lid shown in FIG. 15;
 FIG. 18 is a left-side view of the combined tablet device base and lid shown in FIG. 15;
 FIG. 19 is a right-side view of the combined tablet device base and lid shown in FIG. 15;
 FIG. 20 is a front-side view of the combined tablet device base and lid shown in FIG. 15; and,
 FIG. 21 is a rear-side view of the combined tablet device base and lid shown in FIG. 15.
 The broken lines in the drawings illustrate portions of the combined tablet device base and lid that form no part of the claimed design.
